UNITED STATES PATENT OFFICE.

PAUL L. CLARK, OF CHICAGO, ILLINOIS, ASSIGNOR TO GENERAL ELECTRIC COMPANY, A CORPORATION OF NEW YORK.

SYNCHRONISM-INDICATOR.

No. 848,970.

Specification of Letters Patent.

Patented April 2, 1907.

Application filed October 19, 1903. Serial No. 177,587.

To all whom it may concern:

Be it known that I, PAUL L. CLARK, a citizen of the United States, residing in Chicago, in the county of Cook, in the State of Illinois, have invented certain new and useful Improvements in Synchronism-Indicators, of which the following is a specification.

This invention relates to alternating-current machines; and its object is to provide an indicating device which will accurately designate the instant when it is safe to close the controlling-switch on an alternating-current machine which is coming up to the speed of other machines already running and with which it is to be connected in multiple.

It is well known that in order to safely couple two or more such machines in parallel they must substantially coincide in speed and phase. Ordinarily one or more incandescent signal-lamps are connected in circuit with the machines to be coupled and in shunt to the switch, either across corresponding leads if the method of synchronizing is "dark" or across dissimilar leads if the "bright" method is to be used. As the machine approaches synchronism the fluctuations of the signal-lamps become slower and slower until the operator guesses that the machines are nearly in step. He then throws the switch and trusts to luck to hit the instant when the current-waves most nearly coincide.

My invention aims to provide a device which will indicate very closely the instant when the switch should be closed, thus eliminating all guesswork and the troubles which result from mistakes in judgment on the part of the operator. The invention consists in a small constant-current transformer comprising two relatively movable coils, one of which is operatively connected with an indicator, such as a signal-lamp, the other coil being connected across the controlling - switch. When the machines are not in step, the current in the latter coil repels the other coil and causes them to separate against the tension of a spring. The secondary current induced in the repelled coil at the same time lights up the signal-lamp. As the machines approach in step and the difference in potential decreases the repulsive effect of the primary coil decreases and the secondary coil is moved back by the spring toward a position coincident with the primary until it abuts against a stop. Any further decrease in po-

tential due to the machines coming still closer into step will cause the lamp to darken, and when it goes out the switch may be safely thrown. In other words, the lamp lights up as the exchange of current begins to take place between the machines and attains its maximum brilliancy when the current in the secondary reaches, say, one-half an ampere, (the current for a sixteen-candle-power lamp.) Any further rise in voltage in the primary, due to the machines getting further out of phase, will operate to repel the balanced secondary, whose movement toward a more distant position results in keeping the secondary current at one-half an ampere. The repulsive effect increases through half the period of phase displacement and decreases through the half when the machines are coming back into step. The lamp therefore maintains an even brilliancy until the potential has fallen nearly to zero, and the light diminishes only during the period when there is little exchange of current between the machines. It is thus easy to determine the exact instant when the switch may be safely closed.

In the accompanying drawings, Figure 1 is a diagram of circuits showing my invention. Fig. 2 is a cross-section of the indicating device on a large scale. Fig. 3 is a front elevation, and Fig. 4 is a modification.

The machine 1 is connected with the mains 2 3 4 by the controlling-switch 5 and is supposed to be running at full speed. The machine 6 is coming up to speed, its controlling-switch 7 being open. The primary coil 8 of my indicating device is connected across the switch to similar leads of the circuit. The secondary coil 9 is movable, being preferably pivoted on a transverse shaft 10, journaled in bearings 10', and is maintained yieldingly against a stop 11, preferably by a spring, which may be coiled on the shaft 10, as at 12 in Fig. 4, but is preferably a helical spring 13, attached at one end to a stationary support and at the other to a cord 14, passing over the periphery of a pulley on the shaft 10. The pulley is preferably a cam or eccentric 15 in order to decrease the turning moment of the spring as the secondary rocks away from the plane of the primary. This compensates for the drop in the repulsive effect due to the angular change between the coils and also for the increased tension of the spring as the sec-

ondary coil approaches a position at right angles with the primary, so that the current in the secondary is maintained constant.

The stop 11 is so located that the secondary cannot become exactly parallel with the primary, so that the repulsive effect is always in the same direction. This stop and the bearings 10' are carried on any suitable frame (not shown) which supports the instrument. 10 A bank of lamps 16, controlled by a switch 17, completes the circuit of the indicator.

The operation of my invention has been fully set forth above and need not be repeated.

15 In accordance with the patent statutes I have described the principle of operation of my invention, together with the apparatus which I now consider to represent the best embodiment thereof; but I desire to have it understood that the apparatus shown is only 20 illustrative and that the invention can be carried out by other means.

What I claim as new, and desire to secure by Letters Patent of the United States, is—

25 1. A synchronism-indicator comprising a constant-current transformer responsive to exchange-currents between the machines to be synchronized, and a signal-operatively related to said transformer.

30 2. A synchronism-indicator comprising a constant-current transformer having its primary coil responsive to exchange-currents between the machines to be synchronized, and its secondary coil in circuit with a signal-lamp.

35 3. A synchronism-indicator comprising two relatively movable coils, one responsive to exchange-currents between the machines to be synchronized, and the other connected 40 with an indicating device.

45 4. A synchronism-indicator comprising two relatively movable coils, one responsive to exchange-currents between the machines

to be synchronized and the other connected with a signal-lamp, and means for yieldingly 45 opposing the relative movement of said coils.

5. A synchronism-indicator comprising a transformer having a stationary coil responsive to exchange-currents between the machines to be synchronized, and a pivoted coil 50 connected with the signal-lamp.

6. A synchronism-indicator comprising a transformer having a stationary coil responsive to exchange-currents between the machines to be synchronized, a pivoted coil connected with a signal-lamp, and a spring 55 opposing the movement of said pivoted coil.

7. A synchronism-indicator comprising a transformer having a stationary coil responsive to exchange-currents between the machines to be synchronized and a pivoted coil 60 connected with a signal-lamp, a spring opposing the movement of said pivoted coil, and an eccentric moving with the pivoted coil and to which said spring is connected.

65 8. In a synchronism-indicator, the combination with two or more alternating-current machines, of a signal-lamp, and means for supplying it with constant current during the greater portion of phase displacement of said 70 machines and reducing said current when the machines come nearly in step.

9. In a synchronism-indicator, the combination with two alternating-current machines, of two relatively movable coils which 75 repel each other when the phase displacement of said machines is great, and a signal-lamp which fluctuates in brilliancy when the phase displacement is small and the coils are not moving.

80 In witness whereof I have hereunto set my hand this 15th day of October, 1903.

PAUL L. CLARK.
